UNITED STATES PATENT OFFICE.

HENRY J. SKINNER, OF BRADFORD, PENNSYLVANIA, ASSIGNOR TO LUCIUS W. GODFREY, OF SAME PLACE.

WASHING-MACHINE.

SPECIFICATION forming part of Letters Patent No. 242,163, dated May 31, 1881.

Application filed December 24, 1880. (No model.)

To all whom it may concern:

Be it known that I, HENRY J. SKINNER, a citizen of the United States, residing in Bradford, in the county of McKean and State of Pennsylvania, have invented certain new and useful Improvements in Washing-Machines, of which the following is a specification.

The object of my invention is to provide a convenient and efficient means for washing clothes or other materials, in large or small quantities, without entangling or winding the pieces together, or in any way tearing or injuring them; and the invention consists of two perforated cases for holding the materials to be washed, each case having a suitable cover, a corrugated portion on its inner side, and a crank and connecting-rod, the whole being combined with a suitable water-holding tank or vessel, and arranged so that both of the cases receive an oscillating movement while operating by means of a single crank-pin, and so that while one case is at an incline, or in the act of throwing the clothes to its opposite side, the other is in a horizontal position, as will be more clearly hereinafter shown by reference to the drawings, in which—

Figure 1 represents a side elevation; Fig. 2, a vertical longitudinal section through line X X, Fig. 3. Fig. 3 is a plan or top view. A represents the tub or water-holding vessel. It is provided with two curved water-chambers, a a', (see Fig. 2,) and two washing-cases, B B', arranged to rock or oscillate while in operation on bearings b b' by means of the cranks or arms c c' and connecting-rods d d', which are connected to a crank-pin, C, on the crank-disk D, in the usual way. (See Fig. 1.) The crank-disk D is rigidly fastened to a shaft, D', arranged below the vessel A in suitable bearings or boxes, E. (See Fig. 2.) At the other end of the shaft, opposite the disk D, is fastened a spur-wheel, E', which gears into a pinion, F, on the driving-shaft F'.

G G' represent, respectively, a tight and loose pulley for running the machine.

The washing-cases B B' are provided with covers e, the usual handles, e', and perforations f, arranged in any well-known way. The inner sides of each case are provided with a corrugated surface, H, for the purpose of holding

the clothes or other articles to be washed in the rising side of the case before they drop to the descending side. The water-vessel or tub A is also provided with corrugations or projections H', so as to prevent the water from being thrown out by the rocking action of the cases B B'. 55

It will be noticed that both of the cases do not move exactly alike, so that while the case B' is inclined, as shown, the other case is in a horizontal position, and so that while the clothes are being lifted up at one side of one case they are being thrown down to one side of the opposite case, thereby equalizing the power required to drive them, so that they 65 work easier and more steady than if both cases lifted and moved the clothes at the same time.

The operation of the invention, being simple, will be easily understood without further explanation. 70

I claim—

1. The tub or water-holding vessel A, having the curved chambers a a', the perforated washing-cases B B', set in suitable bearings, 75 and provided with cranks c c', in combination with the connecting-rods d d', crank-pin C, and crank D, connected to the driving mechanism, substantially as and for the purposes set forth.

2. A washing-machine consisting of the tub 80 A, perforated washing-cases B B', cranks c c', and connecting-rods d d', connected to the crank-pin and crank, substantially as specified, so that both washing-cases receive their movements from a single crank-pin, as and for the 85 purposes described.

3. The cranks c c', connected to the cases B B', substantially as specified and shown, in combination with the connecting-rods d d', crank-pin C, crank D, and crank-shaft D', 90 whereby the perforated washing-cases receive different movements, so that when one case is in a horizontal position the other is in an inclined position, as and for the purposes described.

HENRY J. SKINNER.
